CLAIM

The ornamental design for a candy mold, as shown and described.

DESCRIPTION

FIG. 1 is a rear, top perspective view of a candy mold; FIG. 2 is a front, bottom perspective view of a candy mold;

FIG. 3 is a rear view of a candy mold;

FIG. 4 is a front view of a candy mold;

FIG. 5 is a right side view of a candy mold;

FIG. 6 is a left side view of a candy mold;

FIG. 7 is a top view of a candy mold;

FIG. 8 is a bottom view of a candy mold;

FIG. 9 is a right side cross-sectional partial view of a candy mold along line 9 shown in FIG. 3;

FIG. 10 is a top cross-sectional partial view of a candy mold along line 10 shown in FIG. 3;

FIG. 11 is a detail view of portion 11 shown in FIG. 1;

FIG. 12 is a detail view of portion 12 shown in FIG. 2;

FIG. 13 is a detail view of portion 13 shown in FIG. 3;

FIG. 14 is a detail view of portion 14 shown in FIG. 4;

FIG. 15 is a detail view of portion 15 shown in FIG. 6;

FIG. 16 is a detail view of portion 16 shown in FIG. 8;

FIG. 17 is a detail view of portion 17 shown in FIG. 9; and,

FIG. 18 is a detail view of portion 18 shown in FIG. 10.

The broken lines showing portions of the article and boundaries of the detail views form no part of the claimed design.

1 Claim, 15 Drawing Sheets
